UNITED STATES PATENT OFFICE

JOHN J. N. VAN HAMERSVELD, OF CLEVELAND HEIGHTS, OHIO, ASSIGNOR TO THE
WARNER & SWASEY COMPANY, OF CLEVELAND, OHIO, A CORPORATION OF OHIO

INDICATOR

Application filed December 23, 1929. Serial No. 415,904.

This invention relates to an indicator for indicating the rate of movement of a part of a machine, the indicator being of the general type described and claimed in a prior application filed in the name of William J. Burger, Serial No. 345,399, and in a prior application filed in the name of John J. N. Van Hamersveld, Serial No. 409,411.

An indicator of this type is preferably utilized in connection with the control members or levers which control the rate of movement of the part in question, and though it may be utilized very advantageously on or in connection with various types of machines, it is especially useful when applied to a lathe in association with the levers which control the speed or rate of movement and the direction of movement of the work spindle. For that reason, the invention, as in the prior applications referred to, is illustrated as applied to the headstock of a lathe in association with the levers controlling the work spindle. This indicator, as in the prior applications referred to, preferably includes two indicating devices or movable indicating members which by their conjoint movements make it possible for the operator to see at a glance the rate of movement of the controlled part regardless of the position of the several control levers or the order in which they are moved.

It is common in lathes to arrange the levers which control the work spindle at the top of the headstock, and it has been proposed more recently to arrange part of the levers at the top and part of them at the front of the headstock, those at the top of the head stock projecting toward the front side of the machine and those on the front projecting upwardly. In either event, the operating ends of the levers are located so that they may be conveniently operated by the operator standing in front of the machine.

The arrangement and grouping of the control members or levers and the manner

in which said members or levers are operatively connected or associated with the part to be controlled form per se no part of the invention covered by the present application but constitute the subject matter of a co-pending application of John J. N. Van Hamersveld, Serial No. 514,649, filed February 9, 1931.

The principal object of the present invention is to provide an indicator for the purpose stated adaptable for the arrangement of levers last referred to.

A further object is to provide certain improvements in the indicator itself.

The invention may be further briefly summarized as consisting in certain novel combinations and arrangements of parts and details of construction which will be described in the specification and set forth in the appended claims.

In the accompanying sheets of drawings wherein I have shown a preferred and a modified construction, Fig. 1 is a view partly in elevation and partly in section looking toward the front end of the headstock of a lathe with my improved indicator mounted on the headstock in association with the work spindle controlling levers, part of which are arranged on top of the headstock and part at the front side of the headstock; Fig. 2 is a fragmentary elevation looking at a part of the mechanism from the point of view indicated by the line 2-2 of Fig. 1; Fig. 3 is a fragmentary plan view of Fig. 1 showing the two upper levers in certain relative positions; Fig. 4 is a similar view showing these levers in still other relative positions; Fig. 5 is a fragmentary view principally in section, similar to Fig. 1, but showing the parts of the indicator in different positions than shown in Fig. 1, the positions of the indicating members corresponding to the relative positions of the levers shown in Fig. 4, whereas in Fig. 1 the indicating members are in positions corresponding to the relative posi-

tions of the levers shown in Fig. 3; Fig. 6 is a detail sectional view substantially along the line 6—6 of Fig. 1; Fig. 7 is a view corresponding to Fig. 1 showing a modification; 5 Fig. 8 is a sectional view substantially along the line 8—8 of Fig. 7; and Fig. 9 is a plan view of Fig. 7.

Referring now to the drawings, 10 represents the body of the headstock having a 10 cover plate 10^a and a front wall 10^b. I have indicated the work spindle only generally by the reference character 11, but I have omitted, for the sake of clearness, the mechanism for rotating the work spindle at varying speeds 15 in opposite directions inasmuch as this mechanism, including a clutch and several sliding gear cones by which the spindle may be started and stopped or rotated in either direction at a plurality of speeds from a constant speed 20 driving shaft, forms no part of the present invention and may assume widely different forms in the arrangement and details of the driving parts. In the prior Burger application referred to above, there is illustrated 25 the complete movement transmitting mechanism in the headstock, including three sliding gear cones, one being a three-step gear cone and the other two being two-step gear cones, the arrangement illustrated being adapted 30 for work spindle control levers all arranged at the top of the headstock. Similar mechanism, including the identical parts but with a slightly different arrangement of some of the parts, may be employed with the arrangement 35 of the work spindle control levers herein illustrated.

As in the Burger and Van Hamersveld applications referred to above, I have illustrated four levers for controlling the work 40 spindle, one being a clutch controlling lever and the other three being speed controlling levers. This number of levers with a driving mechanism in the headstock involving a three-step gear cone and two two-step gear 45 cones enables twelve different speeds to be imparted to the work spindle both for forward and reverse rotation. The levers referred to are designated 12, 13, 14 and 15 in Figs. 1 to 6. Levers 12 and 13 are mounted 50 coaxially on the top of the headstock, the lever 12 being secured to a vertically disposed shaft 16 and the lever 13 being secured to a sleeve 17 which surrounds the shaft, both the 55 sleeve and the shaft extending through a boss 18 projecting upwardly from the top of the headstock, as illustrated in Fig. 1. The clutch controlling lever 15 at the front of the headstock is secured to a horizontally disposed shaft 19, and the speed controlling 60 lever 14 is secured to a sleeve 20 which surrounds the shaft, both the shaft and the sleeve extending through a horizontally projecting boss 21 on the lower front side of the headstock. The upper levers 12 and 13 project

forwardly and the front levers 14 and 15 project upwardly, their operating ends being closely associated and in convenient reach of the operator standing in front of the headstock. The inner ends of the rock shafts 16 70 and 19 and of the sleeves 17 and 20 will be provided with the usual clutch and gear cone shifting members.

The indicator of Figs. 1 to 6 consists of two indicating devices 22 and 23, the former being provided with an upper row and a lower row of spaced indicia 24 (see Figs. 5 and 8), the indicia preferably being in the form of numerals which, when the indicator is applied to the headstock of a lathe, indicate the revolutions per minute of the work spindle. It is not essential, however, that the indicating characters be in the form of numerals as any other suitable indicia which are directly or indirectly indicative of the rate of movement 80 of the work spindle or other controlled part may be employed. The other indicating device 23 has an opening or window 25 through which the indicia may be observed for any particular speed of the work spindle. There may be provided below the window 25 a second opening 26 so as to avoid having any of the indicia hidden from the view of the operator when the window is in line with the upper row of indicia 24, though this additional opening is not essential to the invention and may be omitted if unnecessary for the convenience of the operator. It might be here stated that the indicating device 22 is capable of being rocked about an axis and may also be elevated so as to bring either row 90 of indicia in line with the window 25, and the indicating device 23 is capable of being rocked about an axis to position the window preferably in one of three different positions, the two movements which may be imparted to the indicating device 22 and the movement which may be imparted to the indicating device 23 making it possible to give a reading or 100 visual indication of any one of the twelve 110 permissible speeds.

The indicating device 22 has at the front a segment or arc-shaped portion 27 on which the indicia are mounted (see particularly Figs. 3, 4 and 5), and inwardly of the segment 115 it has a boss 28 fixed to the upper end of a pin 29 slidably mounted in a sleeve-like boss 30 extending downwardly from a bracket 31 which is mounted for rocking movement on the top of the headstock. In this instance, this bracket is mounted on an integral forward extension of the cover plate 10^a of the headstock, but this is not essential as it may be mounted on a support constituting a part of an attachment which may be suitably secured to a portion of the headstock. The bracket 31 carries between a pair of upstanding ears on a pin 32 a lever 33 which is mounted on the pin midway between its ends. The forward end of the lever has a pin and slot 120 130

connection indicated at 34 with the rearward portion of the indicating device 22 so that when the lever is rocked about the axis of pin 32 the indicating device will be raised or lowered, as the case may be, along with the pin 29. The opposite end of the lever 33 is forked, the forked end straddling a portion of a pin 35 between two shoulders of the pin, this pin being carried by the speed controlling lever 13 and projecting upwardly above the lever 13, as viewed in Fig. 1. The lever 33 normally tends to stand in the position shown in Fig. 1 with its rear end elevated as gravity acting on the indicating device 22 and pin 29 would tend to hold the parts in the relative positions shown, but the action of gravity in this respect may be supplemented by a suitable spring, and in Fig. 1 I have shown a spring actuated plunger 36 for this purpose.

On account of the forked connection between the rear end of the lever 33 and the pin 35, it will be obvious that when lever 13 is rocked or swung from one position to another, as, for example, from the position shown in Fig. 3 to the position shown in Fig. 4, or vice versa, the lever 33, bracket 31, and the indicating device 22 will swing as a unit about the axis of the pin 29, thus moving the curved face of the segment carrying the indicia one space relative to the window 25.

The lever 12 has a camming extension 37 which is adapted to engage the upper end of the pin 35. The two positions of lever 12 are indicated in Figs. 3 and 4, and the throws of the levers 12 and 13 are such that when lever 12 is in the position shown in Fig. 3 lever 13 may be moved from one of its operative positions to the other without having the position of the pin 35 changed by the camming extension 37 of the lever 12. That is to say, the movement of lever 13 from one position to another will simply cause a horizontal rocking movement of the indicating device 22. On the other hand, when lever 12 is moved to its other operative position shown in Fig. 4, the camming extension 37 engages and depresses the pin 35 to the position shown in Fig. 5. This causes the lever 33 to be rocked vertically from the position shown in Fig. 1 to the position shown in Fig. 5, and elevates the indicating device 22 to the position shown in Fig. 5, with the lower row of indicia in line with the window 25. If lever 13 is rocked when lever 12 is in the position shown in Fig. 4, it will cause the indicating device 22 to be rocked as before, except that this indicating device will be retained in its upper position shown in Fig. 5 as long as lever 12 remains in the position shown in Fig. 4.

Lever 15 is a clutch controlling lever which has no effect on the indicator, but the speed controlling lever 14 which, along with the lever 15, is mounted in front of the headstock, as before explained, shifts the indicating device 23 when it (lever 14) is moved from one

operating position to another. In order that this may be accomplished, the indicating device 23 is provided at its inner end beneath the headstock extension on which the bracket 31 is mounted with a cup-like portion 38 having a bearing for rocking movement on the lower end of the sleeve-like boss 30 of the bracket 31. It also encloses a nut 39 which is screwed onto a portion of the sleeve-like extension 30 of the bracket 31 to hold the bracket against upward movement on its support. The lower part of the cup-like portion 38 is formed with a boss which is pinned or otherwise secured to the upper end of a vertically disposed rock shaft 40 which is mounted for rocking movement in a suitable support consisting in this instance of a boss 41 formed on the front wall of the headstock. Obviously, this support for the rock shaft 40 may be a separate member attached to the front wall of the headstock. This rock shaft is capable of a rocking movement only, being held from endwise movement in its support 41. Secured to the lower end of this rock shaft 40 is a forked arm 42 having a forwardly projecting forked portion formed by arms 43 which straddle the lever 14 so that when the lever 14 is rocked from one position to another the forked arm 42, the rock shaft 40, and the indicating device 23 carrying the window 25 will be correspondingly rocked. As indicated in Fig. 6, the lever 14 is a three-position lever, as it preferably controls a three-step gear cone, and, accordingly, the forked arm 42 and the indicating device 23 have three different positions. In this instance, the lower portion of the support 41 for the rock shaft 40 is provided with a depending flange open at the front, and the forward faces of this flange are preferably machined and are adapted to be engaged by the arms 43 of the forked bracket 42 when the latter is in its two extreme positions indicated by dotted lines in Fig. 6.

The levers 12 and 13 are each two-position levers, and the throws of these levers and the proportioning of the parts associated with the indicating device 22 are such that as the levers 12 and 13 are manipulated the indicating device 22 will be given a lateral swinging or rocking movement about the axis of the pin 29 equivalent to one space on the indicia covered face of member 22 and will be moved vertically, either up or down as the case may be, so as to position one row of the indicia or the other in front of the window. On the other hand, the indicating device 23 is not only swung or rocked laterally to three different positions when the lever 14 is moved to its three positions, but the throw of this lever and the proportioning of the parts which actuate the member 23 are such that when the lever 14 is moved from one position to another, the window of the indicating device 23 will be moved a distance equal to two spaces on the indicia covered face of the in-

dicating device 22. By this arrangement any one of the twelve permissible speeds of the work spindle will be indicated by the positioning of the proper speed indicating 5 indicia behind the window 25 through the manipulation of the speed controlling levers.

In Figs. 7, 8 and 9 I have shown a modification wherein the same results are obtained as described above with two indicating 10 devices of the same general type as explained above but arranged and operated somewhat differently with, however, the same arrangement of levers as in the construction first described. In this instance the 15 four levers are designated 12^a, 13^a, 14^a and 15^a, these corresponding in their arrangement, mounting and function to the levers 12, 13, 14 and 15 respectively. The indicia carrying indicating member 44, which corresponds to 20 the member 22 of the first described construction, is pivotally mounted by means of a pin 45 on the lower side of the lever 13^a, which, along with the lever 12^a, is mounted on the top of the headstock. Obviously, 25 when the lever 13^a is swung horizontally it will swing or rock the member 44 horizontally, and the throw of the lever and the proportioning of the parts are such that as the lever 13^a is swung from one operative position to 30 the other the front segment-shaped face 46 of this indicating device will move through a distance equal to one space in so far as the spacing of the indicia is concerned.

This indicating device 44 has an upward 35 extension 47 which projects through a slot in the lever 13^a, as indicated in Fig. 9, and is adapted to be engaged by a cam 48 in the form of an extension on the lower side of the lever 12^a which is mounted coaxially with the 40 lever 13^a. The arrangement is such that when the lever 12^a is in its right-hand position, indicated in Fig. 9, the extension 47 of the indicating device 44 engages the cam 48 of the lever 12^a and holds the forward end of 45 the indicating device in lowered position, as indicated in Fig. 7, so that the upper row of indicia lies opposite the window to be referred to, as shown in Fig. 8, and while lever 12^a occupies the position just stated, the lever 50 13^a can be moved from one operative position to the other without changing the elevation of the forward end of the indicating device 44. However, when lever 12^a is thrown 55 to its left-hand position, the cam 48 is moved laterally from the range of movement of the extension 47, whereupon a spring acting on a plunger 49 elevates the forward end of the indicating device 44 against a stop on the lower side of lever 13^a so as to bring the lower 60 row of indicia opposite the window and the indicating device stays in the position just stated while the lever 13^a is swung from one operative position to the other as long as the lever 12^a remains in its left-hand position.

65 The other indicating device is in the form

of an arm 51 which has sliding engagement on the cover plate 10^a of the headstock. It is provided at its inner end with a hub portion 52 which has a bearing for rocking movement on a hub 53 forming a portion of the cover plate 10^a and located immediately beneath the hub of the lever 13^a. At its forward end, the arm 51 has a downward extension 54 which may, if desired, have an inwardly extending lip 55 to slidably engage 70 the under side of the projecting portion of the cover plate 10^a as indicated in Fig. 7. The lower end of this extension is forked and the forked ends straddle a pin 56 extending inwardly from the three-position speed controlling lever 14^a mounted coaxially with the clutch controlling lever 15^a on the front of the headstock. The upper or horizontal part of this arm carries a window 57 through which either row of indicia may be viewed, 75 and below this window there may be another opening so that none of the indicia characters will be obstructed by the window supporting member, regardless of whether the front end of the indicating device is elevated or lowered. 80 The arrangement is such that as the lever 14^a is moved from one of its three operative positions to another position, the indicating device 51 will be rocked and move the window 57 a distance equivalent to two spaces 85 of indicia precisely as is the case with the construction first described.

With this arrangement, as before, regardless of which levers are manipulated or the order in which they are manipulated, the 100 particular speed or rate of rotation of the work spindle will be indicated by the proper indicia standing behind the window 57.

Thus it will be seen that I have provided an indicator for the purpose described, with 105 the parts arranged in two different ways and associated with control levers having an entirely different arrangement than in the applications first referred to, and while I have shown only two forms of my invention, other 110 changes and modifications may be made without departing from the spirit and scope of the invention as set forth in the appended claims.

Having thus described my invention, I 115 claim:

1. An indicating device for indicating the rate of movement of a part of a machine associated with members for controlling such part, said device being operated by said members, one of which has a plane of movement at an angle to the plane of movement of another.

2. An indicating device for indicating the rate of movement of a part of a machine associated with members for controlling such part, said device being movable in two different directions by said members, one of which moves in a plane at an angle to the plane of movement of another.

3. An indicator for indicating the rate of movement of a part of a machine associated with members for controlling such part, said indicator including two relatively movable devices, one of which is operated by said members, one of the latter being movable in a plane at an angle to the plane of another. 5
4. An indicator for indicating the rate of movement of a part of a machine associated with members for controlling such part, said indicator comprising two movable devices which are operated by said members, one movable in a plane at an angle to the plane of movement of the other. 10
5. An indicator for indicating the rate of movement of a part of a machine associated with a plurality of members for controlling such part, said indicator being composed of two movable indicating devices, one movable in two different directions and both moved by said members, at least one of which is movable in a plane at an angle to the plane of movement of another of said members. 15
6. The combination with a part of a machine whose rate of movement is to be indicated, of control members for such part, a stationary member adjacent said control members, and an indicator including two movable indicating devices adapted to be actuated by certain of said control members, one of said devices having a mounting on said stationary member. 20
7. The combination with a part of a machine whose rate of movement is to be indicated, of control members for such part, a stationary member adjacent said control members, and an indicator including movable indicating members adapted to be actuated by certain of said control members, one of said indicating members having a mounting on said stationary member and another indicating member being supported by one of said control members. 25
8. The combination with a part of a machine whose rate of movement is to be indicated, of control members for such part, a stationary member adjacent said control members, and an indicator including movable indicating devices adapted to be actuated by certain of said control members, one of said devices being mounted for rocking movement on said stationary member. 30
9. The combination with a part of a machine whose rate of movement is to be indicated, of control members for such part, a stationary member adjacent said control members, and an indicator including movable members adapted to be actuated by certain of said control members, one of said members of the indicator being mounted for rocking movement on said stationary member and another having a mounting on one of said control members. 35
10. The combination with a lathe having a headstock with a work spindle and members for controlling the rate of movement of the work spindle, of an indicator associated with said control members and comprising a plurality of relatively movable members including one mounted on the headstock and another supported by one of the control members. 40
11. The combination with a lathe having a headstock with a work spindle and control members for controlling its rate of movement, of an indicator for indicating the rate of movement of the work spindle and comprising a plurality of movable members adapted to be shifted by certain of said control members, one of said movable members being mounted on the headstock and another having a mounting on one of said control members. 45
12. The combination with a lathe having a headstock with a work spindle and with control members mounted partly on top of the headstock and partly in front of the headstock for controlling the rate of movement of the work spindle, of an indicator for indicating the rate of movement of the work spindle and operated by said control members. 50
13. The combination with a lathe having a headstock with a work spindle and with control members mounted partly on top of the headstock and partly in front of the headstock for controlling the rate of movement of the work spindle, of an indicator for indicating the rate of movement of the work spindle and operated by said control members, said indicator including a device movable in two directions by certain of said control members. 55
14. The combination with a lathe having a headstock with a work spindle and with control members mounted partly on top of the headstock and partly in front of the headstock for controlling the rate of movement of the work spindle, of an indicator for indicating the rate of movement of the work spindle and operated by said control members, said indicator including relatively movable devices, one mounted on the headstock and another on one of the control members. 60
15. The combination with a lathe having a headstock with a work spindle and with control members mounted partly on top of the headstock and partly in front of the headstock for controlling the rate of movement of the work spindle, of an indicator for indicating the rate of movement of the work spindle and operated by said control members, said indicator including movable members, one mounted for movement by a lever at the top of the headstock and another mounted for movement by a lever at the front of the headstock. 65
16. The combination with a lathe having a headstock with a work spindle and with control members mounted partly on top of the headstock and partly in front of the headstock for controlling the rate of movement of the work spindle, of an indicator for indicating the rate of movement of the work spindle and operated by said control members, said indicator including movable members, one mounted for movement by a lever at the top of the headstock and another mounted for movement by a lever at the front of the headstock. 70

the headstock and partly in front of the headstock for controlling the rate of movement of the work spindle, of an indicator for indicating the rate of movement of the work spindle and operated by said control members, said indicator including movable devices adapted to be shifted by control members both at the top and at the front of the headstock and supported adjacent thereto for rocking movement.

10 In testimony whereof, I hereunto affix my signature.

JOHN J. N. VAN HAMERSVELD.
